UNITED STATES PATENT OFFICE.

DAVID ALCORN, JR., AND ROBERT A. BLAKE, OF NEW YORK, N. Y.

CORSET-STEEL FASTENING.

SPECIFICATION forming part of Letters Patent No. 317,699, dated May 12, 1885.

Application filed October 23, 1884. (No model.)

To all whom it may concern:

Be it known that we, David ALCORN, Jr., and ROBERT ANDREW BLAKE, of the city, county, and State of New York, have invented certain 5 new and useful Improvements in Corset-Steels, of which the following is a full, clear, and exact description.

Reference is to be had to the accompanying drawings, forming a part of this specification, 10 in which similar letters of reference indicate corresponding parts in all the figures.

Figure 1 is a front elevation of the upper part of a pair of corset-steels to which our improvement has been applied. Fig. 2 is a sectional plan view of the same, taken through the line *xx*, Fig. 1. Fig. 3 is a front elevation of one of the eye-plates. Fig. 4 is a front elevation of one of the locking-hooks.

The object of this invention is to prevent 20 corset-steels from becoming accidentally disconnected.

The invention consists in the peculiar construction and arrangement of parts, as herein-after fully described, and pointed out in the 25 claim.

A B represent a pair of corset steels, to one of which are attached a number of eye-plates, C, to engage with a corresponding number of knobs, D, attached to the other 30 steel. The eyes of the plates C are made sufficiently large at their inner ends to allow the heads of the knobs D to pass through, and only large enough at their outer ends to receive the necks of the said knobs. The shanks 35 of the eye-plates C are secured to the steel A by rivets E, and the shanks of the knobs D are riveted to the steel B.

To the shanks of the eye-plates C, between the rivets E, are pivoted, by rivets F, the 40 shanks of hook-plates G. The outer parts of

the hook-plates G are made wide, and are slotted from their lower edges upon the arcs of circles having their centers at the rivets F, the said slots being made wide enough to receive the necks of the knobs D.

Upon the upper edges of the outer ends of the hook-plates G are formed thumb-pieces H, for convenience in raising the said hook-plates G off the necks of the knobs D, to allow the eye-plates C to be disconnected from 50 the said knobs D.

The hook-plates G are kept from swinging down below the eye-plates C when the steels are disconnected by lips I, formed upon the upper edges of the said hook-plates G, and which engage with the upper edges of the said eye-plates C, as shown in Fig. 2.

With this construction the steels can be connected and disconnected only when the hook-plates G are raised, and when the said 60 steels are connected and the hook-plates G are lowered upon the necks of the knobs D the steels will be locked together and cannot become disconnected accidentally.

Having thus described our invention, we 65 claim as new and desire to secure by Letters Patent—

In a clasp for corset-steels the combination, with the eye-plates C, of the hook-plates G, pivoted to the said eye-plates, and provided 70 with the lips I, for engaging the upper edges of the eye-plates, to limit their downward movement, substantially as herein shown and described.

DAVID ALCORN, JR.
ROBERT A. BLAKE.
